UNITED STATES PATENT OFFICE

148,908

DESIGN FOR AN EAR DRUM PROTECTOR

Jacob J. Cantor, Los Angeles, Calif.

Application September 11, 1943, Serial No. 111,099

Term of patent 14 years

(Cl. D83—1)

To all whom it may concern:

Be it known that I, Jacob J. Cantor, a citizen of the United States, residing at 1901 Beverly Boulevard, Los Angeles, California, have invented a new, original, and ornamental Design for an Ear Drum Protector, of which the following is a specification, reference being had to the accompanying drawing, forming part thereof.

Referring to the drawing:

Figure 1 is a perspective view of an ear drum protector showing my new design;

Figure 2 is a side elevational view thereof;

Figure 3 is a view showing one end thereof; and,

Figure 4 is a view showing the opposite end thereof.

I claim:

The ornamental design for an ear drum protector, as shown.

JACOB J. CANTOR.
